United States Patent

Des. 235,576
Patented June 24, 1975

235,576

COMBINED RADIO AND FOOD SERVICE DISH

Morris Fink, Great Neck, N.Y.

Filed July 11, 1973, Ser. No. 378,345

Term of patent 14 years

Int. Cl. D14—03

U.S. Cl. D56—4 B

FIG. 1

FIG. 2

FIG. 3

FIG. 4

FIG. 1 is a front perspective view of a combined radio and food service dish showing my new design;

FIG. 2 is a top plan view;

FIG. 3 is a side elevational view; and

FIG. 4 is a bottom plan view.

I claim:

The ornamental design for a combined radio and food service dish, as shown and described.
